Inventor,

Max C. Zange.

UNITED STATES PATENT OFFICE.

MAX C. ZANGE, OF NEW HAVEN, CONNECTICUT.

DRAWING INSTRUMENT.

SPECIFICATION forming part of Letters Patent No. 699,738, dated May 13, 1902.

Application filed December 30, 1901. Serial No. 87,803. (No model.)

To all whom it may concern:

Be it known that I, MAX C. ZANGE, a citizen of the United States, residing at New Haven, in the county of New Haven and State 5 of Connecticut, have invented a new Improvement in Drawing Instruments and Similar Tools, of which the following is a full description.

My invention relates to an improvement in 10 drawing instruments and similar tools which are of small thickness and adapted to be reversed face for face, as triangles, curves, protractors, and other instruments.

The accompanying drawings, which form 15 part of this specification, illustrate the improvement.

To facilitate the handling of the instruments, I use a removable handle.

Figure I of the drawings is a plan view of 20 the handle. Fig. II is a view of an elevation of it. Fig. III is a section through its vertical axis C C. Fig. IV is a perspective view showing the handle mounted in a drawing instrument. Fig. V is a plan view of a drawing instrument, showing the handle mounted 25 therein without a bushing or block. Fig. VI is a section through Fig. V at the line x x.

The handle consists of a rod R, sliding in a bushing or block B. From the block or 30 bushing B a projecting part A enters a recess G of the rod, running lengthwise to near each end of the rod, thus forming a stop on each end of the rod, preventing it from dropping out of the bushing and from turning around 35 in same. The bushing is made according to the thickness of the material of the instrument and also the rod so adjusted as not to form an obstruction upon the surface in contact with the work. The assembled handle 40 is secured in a corresponding opening of the instrument, preferably near the center of gravity, and held in place by friction or adhesion.

Where the material and shape of the instrument allow it, the bushing or block may 45 be omitted and the rod be used in connection with a part K, projecting from the instrument, as Figs. V and VI of the drawings show. Part K projects from the middle plane of the 50 instrument and enters the recess of the rod, thus preventing the rod from dropping out of the instrument and from turning around in it.

After turned upside down by the handle the

instrument will slide down the rod by its 55 weight to the supporting-surface, or the rod may be pushed toward the opposite face of the instrument to act as handle again. Thus one end of the rod will project above one surface of the instrument, while the other end is 60 flush with the lower surface thereof.

Having fully described my invention, what I claim as new, and desire to secure by Letters Patent, is—

1. The combination with a flat drawing instrument, adapted to be reversed face for 65 face, of a handle mounted therein, and movable through the instrument to project above whichever face of the instrument is uppermost.

2. The combination with a flat drawing instrument, adapted to be reversed face for 70 face of a handle mounted therein, and movable through the instrument from one face to the other according to the face thereof that 75 is uppermost so that the handle projects above the uppermost face of the instrument, and lies flush with the lower thereof.

3. The combination with a flat drawing instrument, adapted to be reversed face for 80 face, of a sliding handle mounted in the instrument at a right angle to the plane thereof and formed at its ends with stops which limit the movement of the handle in either direction, whereby when the instrument lies 85 on one face the handle will project above its opposite face, and vice versa.

4. The combination with a flat drawing instrument adapted to be reversed face for 90 face, of a bushing mounted therein, and a sliding handle mounted in the bushing, provided with stops at its ends and sliding to project beyond the opposite faces, of the instrument according to which is uppermost.

5. The combination with a flat drawing instrument, of a bushing mounted therein, a stop-piece located in the said bushing, and a sliding handle mounted in the bushing and provided at its ends with stops engaging with the said stop-piece for limiting the movement 95 of the handle in either direction.

In testimony whereof I have signed my name to this specification in the presence of two subscribing witnesses.

MAX C. ZANGE.
